MECHANICAL PENCIL

Herbert W. Sams, Atlanta, Ga., assignor to
Scripto, Inc., a corporation of Georgia

Application May 26, 1948, Serial No. 29,245

9 Claims. (Cl. 120—18)

1

This invention relates to mechanical pencils and more particularly to means for actuating the lead feed mechanisms of such pencils.

In the construction of mechanical pencils of the type comprising a lead feed mechanism housed in a barrel and operated from a ferrule fitted on the top end of the barrel, one of the principal problems is the provision of a simple, efficient means for connecting the operating ferrule for actuation of the lead feed mechanism. Usually the operating ferrule is also used to carry an eraser so that provision must be made for removing the ferrule easily whenever it is desired to replace a worn eraser. Also, the means for connecting the operating ferrule with the lead feed mechanism should provide for restraining reverse movement of the lead feed mechanism under writing pressure while still permitting easy actuation of the lead feed mechanism from the operating ferrule for forward or reverse movement.

According to the present invention the above purposes are accomplished in a particularly effective manner by the provision of a cap member formed for disposition over the top end of the pencil barrel to retain the operating ferrule in place and connect this ferrule for actuation of the lead feed mechanism. Briefly described, the cap member provided according to the present invention comprises a base portion formed for engagement with the lead feed mechanism and wing portions depending from the base portion to overlie the side of the barrel adjacent its top end. These wing portions are formed with bosses adapted for frictional contact with the operating ferrule so that the lead feed mechanism may be driven from the operating ferrule, and the wing portions are further arranged so that they are pressed in frictional contact with the side of the barrel adjacent its top end by the operating ferrule to restrain reverse movement of the lead feed mechanism under writing pressure, as described more in detail below in connection with the accompanying drawing illustrating the present invention, in which:

Fig. 1 is a side elevation, partly in section, of a mechanical pencil incorporating a cap member arranged according to the present invention;

Fig. 2 is a fragmentary sectional detail of the top end of the pencil shown in Fig. 1;

Fig. 3 is a section taken on the line 3—3 in Fig. 2;

Fig. 4 is a side elevation of the cap member used according to the arrangement illustrated in

2

Figs. 1 to 3, inclusive, for connecting the operating ferrule with the lead feed mechanism;

Fig. 5 is a fragmentary sectional detail corresponding generally to Fig. 2, but illustrating a modified form of cap member embodying the present invention;

Fig. 6 is a section taken on the line 6—6 in Fig. 5;

Fig. 7 is a side elevation of the cap member used according to the arrangement illustrated in Figs. 5 and 6;

Fig. 8 is a fragmentary sectional detail corresponding generally to Figs. 2 and 5, but showing a further alternative arrangement of a cap member embodying the present invention;

Fig. 9 is a section taken on the line 9—9 in Fig. 8; and

Fig. 10 is a side elevation of the cap member used according to the arrangement shown in Figs. 8 and 9.

The mechanical pencil shown in Fig. 1 of the drawing is of the same general type disclosed in the copending application of Blanchard D. Smith, Serial No. 634,271, filed December 11, 1945, and comprises a barrel 25 housing a lead feed mechanism indicated generally by the numeral 26. The lead feed mechanism 26 comprises a longitudinally slotted lead guide tube 27, and a lead gripping and ejecting mechanism 28. The lead gripping and ejecting mechanism 28 includes a propelling member 29 formed with external screw threads engaging internal screw threads 30 in the barrel 25 for feeding movement of lead 31 at the writing end of the barrel 25 upon rotation of the lead guide tube 27. Reference is made to the above identified copending application for further details of the operation of the lead feed mechanism 26 in this manner.

The lead feed mechanism 26 is positioned and retained in the barrel 25 by an assembly cap 32 fixed over the top end of the barrel 25 by dimpling or the like as indicated at 33. The lead guide tube 27 extends slightly from the top end of the barrel 25 through a central aperture at 34 in the assembly cap 32, and the guide tube 27 is formed with ears 35 struck out below the assembly cap 32 so that the guide tube is retained in the barrel 25 but is free for rotation (compare Fig. 2).

A cap member 36 formed according to the present invention is disposed over the assembly cap 32 at the top end of the barrel 25. This cap member 36 comprises a base portion 37 formed for engagement with the extending end of the lead guide tube 27, and wing portions 38 depending from the base portion 37 to overlie the side of the

barrel 25, i. e., the assembly cap 32, adjacent its top end. For engagement with the lead guide tube 27, the base portion 37 of the cap member 36 is formed with a central aperture 39 fitting over the lead guide tube 27 and having a protruding lug portion 40 shaped to engage the longitudinal slot in the guide tube 27, so that the guide tube 27 is keyed for rotation with the cap member 32. Above the base portion 37, further ears 41 are struck out on the guide tube 27 to 10 retain the cap member 36 in place on the top end of the barrel 25.

As previously mentioned, the depending wing portions 38 are formed with bosses 42 adapted for frictional contact with the operating ferrule 15 43 which retain the operating ferrule 43 in place at the top end of the barrel 25 and connect it through the cap member 36 for driving the lead feed mechanism 26. In the form of a cap member illustrated in Figs. 1 to 4, inclusive, of the drawing, the bosses 42 are centrally disposed on the wing portions 38, and four wing portions 38 are preferably provided so that the bosses 42 are regularly spaced circumferentially 90° apart. The top end of the operating ferrule 43 may be arranged, as shown, to carry an eraser 44, if desired.

The wing portions 38 are further formed with a transverse curvature differing from the curvature of the exterior surface of the barrel 25, or assembly cap 32, adjacent its top end. In the form of cap member 36 illustrated in Figs. 1 to 4, inclusive, of the drawing, the wing portions 38 are formed with a greater transverse curvature, i. e., are formed on a smaller radius, than the exterior surface of the barrel 25, so that the wing portions 38 are disposed for frictional contact with the side of the barrel 25 adjacent their lateral side edges, and are centrally spaced from the side of the barrel 25 (compare Fig. 3).

As mentioned above, the bosses 42 are centrally disposed on the wing portions 38, so that they are consequently located at the above noted point of central spacing of the wing portions 38 from the side of the barrel 25. As a result, when the operating ferrule 43 is fitted on the top end of the barrel 25, frictional contact with the bosses 32 causes the wing portions 38 to be forced inwardly against the side of the barrel 25 so that the wing portions 38 are pressed adjacent their lateral side edges in frictional contact with the side of the barrel 25. This frictional contact on the barrel 25 imposes a drag on operation of the lead feed mechanism 26 so that the tendency for reverse movement of the lead feed mechanism 26 under writing pressure when the pencil is in use is effectively restrained. The manner in which the wing portions 38 are formed according to the present invention with a curvature differing from that of the barrel 25 provides a spring action for effecting the above described frictional contact with the side of the barrel 25 which maintains the frictional contact substantially uniform despite the tolerance which must be allowed in manufacturing operations.

A modified form of cap member 45 arranged according to the present invention is illustrated in Figs. 5 to 7, inclusive, of the drawing. As in the case of the first embodiment described above, the cap member 45 comprises a base portion 46 and depending wing portions 47. The base portion 46 in this instance is generally rectangular and is formed with an aperture 48 having a protruding lug portion 49 engaging the lead guide

tube 27 as previously described. The wing portions 47, however, differ from those in the embodiment previously described in that these wing portions 47 are extended laterally at both side edges and formed with a curvature less than that of the barrel 25, so that the wing portions 47 are spaced from the side of the barrel 25 adjacent their lateral side edges. Bosses 50 adapted for frictional contact with the operating ferrule 43 and are formed on the wing portions 47 adjacent these lateral side edges, so that it is the central section of the wing portions 47 that is pressed in frictional contact with the side of the barrel 25 when the operating ferrule 43 is in place. Preferably, the wing portions 47 are extended laterally a sufficient distance to allow the bosses 50 to be regularly spaced circumferentially 90° apart. This arrangement enhances the spring action of the wing portions 47 when they are pressed in frictional contact with the side of the barrel 25 by the operating ferrule 43.

An alternative arrangement of the embodiment just described is illustrated in Figs. 8 to 10, inclusive, of the drawing, in which the cap member 51 is formed with a base portion 52 having an aperture 53 shaped with a protruding lug portion 54 for engagement with the lead guide tube 27, and depending wing portions 55 formed with a transverse curvature less than that of the barrel 25, but extending laterally on only one side. This arrangement further enhances the spring action of the wing portions 55 but involves a somewhat more complicated construction. As in the embodiment illustrated in Figs. 5 to 7 of the drawing, 30 the wing portions 55 are formed with bosses 56 adjacent their lateral side edges for frictional contact with the operating ferrule 43, and the wing portions 55 are preferably extended laterally a distance sufficient to allow the bosses 56 to be regularly spaced circumferentially 90° apart.

I claim:

1. In a mechanical pencil of the type comprising a lead feed mechanism housed in a barrel and operated from a ferrule fitted on the top end of said barrel, a cap member associated with said lead feed mechanism for actuation thereof, said cap member being formed for disposition over the top end of said barrel and having depending wing portions disposed to overlie the side of said barrel adjacent its top end, and said depending wing portions being formed with bosses adapted for frictional contact with said operating ferrule, whereby said lead feed mechanism may be driven from said operating ferrule and said wing portions are pressed in frictional contact with the side of said barrel by said operating ferrule for restraining reverse movement of said lead feed mechanism under writing pressure.

2. In a mechanical pencil of the type comprising a lead feed mechanism housed in a barrel and operated from a ferrule fitted on the top end of said barrel, a cap member disposed over the top end of said barrel for retaining said operating ferrule in place, said cap member having a base portion formed for association with said lead feed mechanism and having wing portions depending from said base portion to overlie the side of said barrel adjacent its top end, and said wing portions being formed with bosses adapted for frictional contact with said operating ferrule, whereby said operating ferrule frictionally grips said bosses for driving said lead feed mechanism and said wing portions are pressed in frictional contact with the side of said barrel by said oper-

ating ferrule, and said operating ferrule is deformed for frictional contact with said barrel, for restraining reverse movement of said lead feed mechanism under writing pressure.

3. A mechanical pencil comprising a barrel, a lead feed mechanism housed in said barrel, a cap member disposed over the top end of said barrel, and an operating ferrule fitted on the top end of said barrel over said cap member, said cap member having a base portion formed for keyed engagement with said lead feed mechanism and having wing portions depending from said base portion to overlie the side of said barrel adjacent its top end, and said wing portions being formed with bosses adapted for frictional contact with said operating ferrule, whereby said lead feed mechanism may be driven from said operating ferrule and said wing portions are pressed in frictional contact with the side of said barrel by said operating ferrule for restraining reverse movement of said lead feed mechanism under writing pressure.

4. In a mechanical pencil of the type comprising a lead feed mechanism housed in a barrel and operated from a ferrule fitted on the top end of said barrel, a cap member disposed over the top end of said barrel for connecting said operating ferrule with said lead feed mechanism for operation thereof, said cap member having a base portion formed for keyed engagement with said lead feed mechanism and having wing portions depending in a symmetrical pattern from said base portion to overlie the side of said barrel adjacent its top end, and said wing portions being formed with bosses regularly spaced circumferentially and adapted for frictional contact with said operating ferrule, whereby said lead feed mechanism may be driven from said operating ferrule and said wing portions are pressed in frictional contact with the side of said barrel by said operating ferrule for restraining reverse movement of said lead feed mechanism under writing pressure.

5. In a mechanical pencil of the type comprising a lead feed mechanism housed in a barrel and operated from a ferrule fitted on the top end of said barrel, a cap member disposed over the top end of said barrel for connecting said operating ferrule with said lead feed mechanism for operation thereof, said cap member having a base portion formed for engagement with said lead feed mechanism and having wing portions depending in a symmetrical pattern from said base portion to overlie the side of said barrel adjacent its top end, said wing portions being formed with a transverse curvature differing from the curvature of the exterior surface of said barrel adjacent its top end, whereby said wing portions are partially spaced from the side of said barrel, and said wing portions being further with bosses positioned on said wing portions at a point spaced from said barrel and adapted for frictional contact with said operating ferrule, whereby said lead feed mechanism may be driven from said operating ferrule and said wing portions are pressed in frictional contact with the side of said barrel by said operat-

ing ferrule for restraining reverse movement of said lead feed mechanism under writing pressure.

6. In a mechanical pencil of the type comprising a lead feed mechanism housed in a barrel and operated from a ferrule fitted on the top end of said barrel, a cap member disposed over the top end of said barrel for connecting said operating ferrule with said lead feed mechanism for operation thereof, said cap member having a base portion formed for engagement with said lead feed mechanism and having transversely curved wing portions depending from said base portion to overlie the side of said barrel adjacent its top end, said wing portions being formed with a greater curvature than the exterior surface of said barrel adjacent its top end, whereby said wing portions are disposed for frictional contact with the side of said barrel adjacent their lateral side edges and are centrally spaced from the side of said barrel, and said wing portions being further formed with centrally positioned bosses adapted for frictional contact with said operating ferrule, whereby said lead feed mechanism may be driven from said operating ferrule and said wing portions are pressed in frictional contact with the side of said barrel by said operating ferrule for restraining reverse movement of said lead feed mechanism under writing pressure.

7. In a mechanical pencil of the type comprising a lead feed mechanism housed in a barrel and operated from a ferrule fitted on the top end of said barrel, a cap member disposed over the top end of said barrel for connecting said operating ferrule with said lead feed mechanism for operation thereof, said cap member having a base portion formed for engagement with said lead feed mechanism and having wing portions depending from said base portion to overlie the side of said barrel adjacent its top end and extending laterally with a transverse curvature less than the curvature of the exterior surface of the barrel adjacent its top end, whereby said wing portions are spaced from the side of said barrel adjacent their lateral side edges, and said wing portions being further formed with bosses positioned adjacent their lateral side edges and adapted for frictional contact with said operating ferrule, whereby said lead feed mechanism may be driven from said operating ferrule and said wing portions are pressed in frictional contact with the side of said barrel by said operating ferrule for restraining reverse movement of said lead feed mechanism under writing pressure.

8. A cap member as defined in claim 7 and further characterized in that said wing portions extend laterally at both sides sufficiently to allow said bosses to be regularly spaced circumferentially 90° apart.

9. A cap member as defined in claim 7 and further characterized in that said wing portions extend laterally at only one side a distance sufficient to allow said bosses to be regularly spaced circumferentially 90° apart.
